UNITED STATES PATENT OFFICE

CARLOS WETZELL, OF FRIEDENAU, NEAR BERLIN, AND WALTHER INHOFFEN, OF WILMERSDORF, NEAR BERLIN, GERMANY, ASSIGNEES TO N. V. INTERNATIONALE AUTOMATEN MAATSCHAPPIJ, LA LANGE VOORHOUT, OF THE HAGUE, NETHERLANDS

COIN-CONTROLLED VENDING MACHINE

Original application filed June 2, 1926, Serial No. 113,217, and in Germany March 6, 1926. Divided and this application filed November 21, 1927. Serial No. 234,850.

The present invention relates to coin-controlled vending machines for small articles such as confectionery and the like.

More especially, the invention relates to coin-controlled vending machines suitable for placing where space is very limited, as, for instance in street cars, busses, railway cars, flying machines, ships, theatres, cinemas and the like.

According to the invention a coin-controlled vending machine is provided, which is of very small dimensions, but nevertheless contains all mechanisms which are necessary for securing a faultless operation of the machine, thereby preventing the occurrence of losses to the possessor of the machine as well as to customers.

The new machine can be used in any connection, but it is particularly designed for use in connection with the detachable structure described in our co-pending application Serial No. 113,217, filed June 2, 1926, of which this application is a division.

In a machine according to the present invention, means are provided for automatically closing the coin inlet opening as soon as the magazine has been emptied. A further feature of this invention consists in that a coin, which may have been inserted during a time when the delivery mechanism has not yet come to its position of rest, will be retained in the coin conduit and prevented from dropping into the delivery mechanism until after the latter has returned to such position.

Most known devices of this kind have the disadvantage that the vending machine is not sufficiently protected against taking out goods in an unlawful way. For instance, an

article may be removed unlawfully from the machine by inserting a suitable implement into the delivery opening after the insertion of the coin and after having taken out the first article in such a manner that the coin will be prevented from falling down but will occupy a position such that it may again be shifted backward until it couples the delivery slide with a second article which may thus also be withdrawn from the machine.

This drawback is effectively avoided ac-

cording to the invention by means of a locking device, which makes a backward shifting of the coin and, hence, the removal of a second article impossible.

A preferred constructional form of the invention is shown by way of example in the accompanying drawing, in which Fig. 1 is a side view of the machine arranged on a back plate, Fig. 2 a front view of the complete mechanism and Fig. 3 a partial horizontal section on line A—A of Fig. 2. Figs. 4, 5 and 6 are detail views illustrating three different positions of the coin in the slide 13.

1 is the casing of the apparatus, 2 the magazine within the same containing the articles to be vended, and 3 an article resting at the bottom of the magazine.

4 denotes the inlet opening or slot for the coins, below which opening a coin chute or conduit 5 is provided within the magazine 2, 70 said conduit having in its rear wall a rectangular recess extending over the length of the same. A spring 7 having at its lower end an extension 6 is placed within the recess, said spring 7 being further provided with a stop 7'. In front of the coin chute 5 is arranged a two-armed lever which is fulcrumed or pivotally supported at the point 8; the lower arm 9 of the lever tending to move away from the chute (that is, to the left) under the influence of a spring 10, thereby bringing the angularly-bent upper arm 11 of said lever directly beneath the coin inlet 4 to close the same. However, this movement of the lever does not occur until the last article 3 has been ejected from the magazine; the articles contained in the magazine normally forcing arm 9 to the right, so that the other arm 10 is moved leftward and uncovers inlet 4.

Below the magazine 2 there are provided two rails 12, between which a free intermediate space is left, the width of which is somewhat smaller than the diameter of the coins to be inserted. At a certain point said free intermediate space is enlarged in such a manner that the coin will be enabled to leave the path provided by the rails and fall downward. The delivery slide 13 is guided by the rails 12, and the slot

14 which is provided in said slide serves for the reception of the coins.

A spring 36 is fastened to the rails 12 below the coin conduit by means of the screws 35, the resilient tongue 37 of said spring projecting into the space between the rails 12. By means of a coin 38 which is shifted forwardly or to the left by the slide 13, the tongue 37 is bent back in such a way as to move out of the space between the rails. In this manner the coin may pass by the tongue which will thereupon move back into the aforesaid space owing to its resiliency. This space will thus be blocked, so that the coin is prevented from being moved in backward direction.

The delivery slide 13 is actuated by means of the rod 15 and the handle 16, while a spiral spring 17 automatically carries back the slide 13 into its rear position after an article has been delivered through the front opening of the machine.

We claim:—

A coin-controlled vending machine comprising, in combination, a magazine for the reception of articles to be vended; a coin conduit; a spring-actuated delivery slide provided with a slot to receive and hold a coin from the coin conduit; a pair of spaced rails for supporting the coin shifted by the slide until it leaves the rails, said rails also forming guides for the slide; and a spring secured to one of said rails below the coin conduit and projecting through the space between the said rails into the path of the coin located in the slot in said slide to be flexed back by the coin during the forward movement of the slide but prevent backward movement of the coin.

40. In testimony whereof we affix our signatures:

CARLOS WETZELL
WALThER INHOFFEN.
